UNITED STATES PATENT OFFICE.

SAMUEL A. LEVIN, OF CHICAGO, ILLINOIS.

DESIGN FOR A DENTAL MOLD.

47,493.

Specification for Design.

Patented June 22, 1915.

Application filed January 25, 1915. Serial No. 4,394. Term of patent 14 years.

To all whom it may concern:

Be it known that I, SAMUEL A. LEVIN, a citizen of the United States, residing at Chicago, in the county of Cook and State of Illinois, have invented a new, original, and ornamental Design for a Dental Mold, of which the following is a specification, reference being had to the accompanying drawing, forming a part thereof.

Figure 1 is a perspective view of a dental

mold showing my new design. Fig. 2 is a side elevation of the mold. Fig. 3 is an end view of the mold.

I claim:

The ornamental design for dental mold, as shown.

SAMUEL A. LEVIN.
